J. PARSONS

CIGARETTE CASE

Filed May 29, 1926

UNITED STATES PATENT OFFICE.

JOHN PARSONS, OF NEWTON CENTER, MASSACHUSETTS.

CIGARETTE CASE.

Application filed May 29, 1926. Serial No. 112,430.

This invention relates to cigarette cases and more especially to such a case for use with so-called self-lighting cigarettes.

An object of the invention is a cigarette case in which is provided a progressively supplied abrasive by means of which the fuses of self-lighting cigarettes may be ignited.

According to this invention, the cigarette case is provided with a cylindrical housing within which is arranged a roll of abrasive tape, the end of which passes through an aperture in the casing to a supporting plate also carried by the cigarette case. Means are provided for rotating the roll within the casing. Preferably the casing is of sufficient length to receive a plurality of rolls and means are provided for feeding the rolls successively into operative relation to the plate as the preceding roll is exhausted. In a cigarette case of the hinged type the casing may form a part of the hinge and the arm usual to such cigarette cases for holding the cigarettes in the case may be used as the supporting plate for the abrasive. In cigarette cases of the type having a removable top, the casing may be arranged in the place normally occupied by one of the cigarettes and the plate for supporting the abrasive may be attached to the exterior of the cigarette receiving portion of the case.

Other objects, novel features and advantages of the invention will be apparent from the following specification and accompanying drawings wherein

Figure 1 discloses a cigarette case of the hinged type embodying the invention.

Figure 2 is a perspective view of such cigarette case with the cover lifted.

Figure 3 is a section on the line 3—3 of Fig. 2.

Figure 4 is a section on the line 4—4 of Fig. 1.

Figure 5 is a view similar to Fig. 3 but with the cover closed.

Figure 6 is a section on the line 6—6 of Fig. 2.

Figure 7 is a perspective view of a detail.

Figure 8 is a section on the line 8—8 of Fig. 2; and

Figure 9 discloses a cigarette case of the removable cover type embodying the invention.

The cigarette case disclosed in Figs. 1 to 8 inclusive comprises a body portion 10 and a cover 11, both having curved portions sur-

rounding a casing 12. An arm or plate 13 also has a curved portion surrounding the casing 12. The body portion 10 and arm 13 are rotatably mounted on the casing 12 whereas the cover 11 is rigidly connected thereto as by welding or soldering. The arm 13 is provided with inturned flanges 14 to form guide slots which terminate in a slot communicating with the interior of the casing 12. Preferably a portion of the arm 13 also extends into the casing 12 and is provided with a knife edge.

Within the casing is provided a shaft 15 carried by a plug 16 rotatably mounted in the end of the casing. A knurled button 17 is carried by the plug 16 and projects beyond the end of the casing 12. The plug 16 is held in the casing 12 by a lock which preferably consists of a single raised thread on the interior of the casing and on the exterior of the block so arranged that the plug may be removed by rotation in one direction only. Within the casing 12 and mounted on the shaft 15 are a plurality of rolls 18 of abrasive tape, one of which abuts against a stop 19 so positioned as to arrange said roll in alignment with the slot in the arm 13. A follower 20 is slidably keyed to the shaft 15 and between it and the plug 16 is interposed a spring 21.

A plurality of rolls 18 are loaded into the casing 12 and the button 17 turned. The face of the follower 20 is milled so that rotation of it causes the roll in contact with it also to rotate. The friction exerted between the various rolls by virtue of the spring 21 causes them all to rotate and the end of the tape of the roll in contact with the stop 19 engages with the knife edge of the arm 13 and is directed through the slot therein. The tape may then be pulled out to the end of the arm 13 with the finger or any suitable instrument. As the abrasive wears from the tape it may be pulled out and thrown off, thus bringing a fresh abrasive surface on to the arm 13. When the first roll has been used up another roll will be brought into position by means of the spring 21 and the button 17 rotated to supply the tape to the arm 13.

The shaft 15 may be solid and grooved to receive a pin on the follower 20 or it may be bifurcated. In the latter event, the inner end of the roll may be passed through the bifurcating slot and rotary movement communicated to the rolls by virtue of this con-

nection. In such case the follower 20 need not have a milled face and need not be keyed to the shaft 15. Preferably the arm 13 is bowed as shown in Fig. 8 so that the face 5 of the tape is at least as high as the faces of the flanges 14. A suitable spring 22 is provided for keeping the arm 13 normally in the position shown in Figs. 2 and 3 to hold the cigarettes in the body portion of the 10 case.

In Figure 9 is disclosed a cigarette case of the removable cover type equipped with the invention. Here the casing 12 is arranged in the position normally assumed by one of 15 the cigarettes and the arm or plate 13 is suitably attached to the outer face of the cigarette receiving portion, there being provided therethrough a slot by means of which the tape passes from the case to the supporting 20 plate 13.

With either of the cigarette cases herein disclosed the abrasive tape may be quickly and easily renewed so that at all times there is provided a proper surface upon which to 25 ignite the fuses of the self-lighting cigarettes for which these cases are especially designed. The tape is progressively renewed from the rollers with very little effort and a single filling of the casing with rolls of tape will 30 provide sufficient abrasive for a long period of use.

It is, of course, understood that various modifications may be made in the structure above described without in any way departing from the spirit of the invention set forth in the appended claims.

Having thus described my invention, what I claim as new and desire to secure by Letters Patent of the United States is:

- 40 1. In a cigarette case, a plate pivoted to said case for holding cigarettes therein, said plate having provision for receiving and guiding an abrasive tape and means for progressively supplying tape to said plate.
- 45 2. In a cigarette case, a plate pivoted to said case for maintaining cigarettes therein, a supply of abrasive material and means for progressively supplying said material to said plate.
- 50 3. In a cigarette case, a casing for receiving a roll of abrasive tape, a plate pivoted to said case for maintaining cigarettes therein, said plate being in alinement with a slot in

said casing through which the tape may pass to said plate and means for rotating 55 the roll in said casing.

4. In a cigarette case, a casing for receiving a plurality of rolls of abrasive tape, a plate in alinement with a slot in said casing through which the tape may pass to said 60 plate, means for rotating said rolls in said casing and means for advancing said rolls into alinement with said slot.

5. In a cigarette case, a casing, a shaft 65 therein on which may be mounted a roll of abrasive tape, a plate in alinement with a slot in said casing through which tape may pass to said plate, means for rotating said shaft and means for communicating rotary movement to said roll from said shaft. 70

6. In a cigarette case, a casing, a shaft therein on which may be mounted a roll of abrasive tape, a follower keyed to said shaft and having a roughened face to engage said 75 roll, a plate in alinement with a slot in said housing through which tape may pass to the plate and means for rotating said shaft.

7. In a cigarette case, a casing, a shaft 80 therein upon which may be mounted rolls of abrasive tape, a plate in alinement with a slot in said housing through which tape may pass to said plate, a follower on said shaft, resilient means for forcing said follower into contact with said rolls, means for rotating said shaft and means for communicating rotary movement from said shaft to 85 said rolls.

8. In a cigarette case, a casing, a shaft in 90 said casing on which may be mounted a plurality of rolls of abrasive tape, a plate in alinement with a slot in said casing through which tape may pass to said plate, said shaft being bifurcated to receive the inner 95 end of the tape of each roll whereby rotary movement may be communicated from the shaft to said rolls and means for rotating said shaft.

9. In a cigarette case, a casing for receiving a roll of abrasive tape, a plate having a slotted portion projecting through an aperture in said casing and means for rotating said roll to engage the end of the tape with one edge of said slot. 100

In testimony whereof, I have signed my name to this specification.

JOHN PARSONS.
